GAUGING MACHINE

Theodore A. Jagen, Harrison, N. J., assignor to
 General Motors Corporation, Detroit, Mich., a
 corporation of Delaware

Application November 15, 1944, Serial No. 565,040

4 Claims. (Cl. 209—88)

1

This invention relates to gauging machines and comprises all of the features of novelty herein disclosed. An object of the invention is to provide an improved gauging machine to measure articles and eliminate those which are oversize or undersize. Another object is to provide a machine to measure each of a series of articles, such as the length of cylindrical rollers, and eliminate those that are too long or too short so that only those of acceptable size need be given a further treatment such as gauging for width or diameter.

To these ends and also to improve generally upon machines of this character, the invention consists in the various matters hereinafter described and claimed. In its broader aspects, the invention is not necessarily limited to the specific construction selected for illustrative purposes in the accompanying drawings in which

Fig. 1 is a plan view of the machine.

Fig. 1A is a plan view of a portion of Fig. 1, the two slides being in a different position and some parts being omitted.

Fig. 2 is a front view partly in section.

Fig. 3 is a left hand side view partly in section.

Fig. 4 is a right hand side view of a portion of the mechanism.

Fig. 4A is a view similar to Fig. 4 with some parts in a different position and with some omitted.

Figs. 5 and 6 are plan views of the two top plates.

Fig. 7 is a perspective view of the floating block and associated mechanism.

Fig. 8 is a view similar to Fig. 1A, the articles being shown in their various positions and the spacer 122 being omitted.

Fig. 9 is a diagram.

The articles to be gauged are herein illustrated as cylindrical rollers which are first gauged for length and then gauged for diameter provided the length is acceptable. The rollers R are urged out of a feed tube 2 which is fastened by a vertical screw 3 against a V-shaped seat 4 on a plate 6 fastened to the front of the machine, the rollers coming from the feed tube being guided at the left by a plate 8 which is slotted and adjustably fastened by a screw to a base plate 10. The rollers are guided at the right by the side of a fixed gauge block 12 fastened by screws and dowels to the base plate. The leading roller abuts against a stop plate 14 which is slotted horizontally and adjustably fastened by a screw to the base plate. A reciprocating slide or pusher 16 has a narrow extension or pusher which pushes

2

the foremost roller sideways between the rear face of the fixed gauge block 12 and a movable gauge member 18 whose head is slightly rounded where the roller enters. An undercut at the end of the pusher tends to press the roller against the base plate to avoid cocking. This movable gauge member 18 actuates mechanism as will appear to determine whether the roller is to be immediately released or allowed to continue for diameter gauging.

As the roller is pushed sideways past the gauge members 12 and 18, if it is within acceptable limits, it takes a supported position between the bevelled edge of the base plate 10 and the bevelled edge of a movable slide 20 slidable in a deep groove of a similarly bevelled base plate 22 which is much thicker than the base plate 10. These bevelled plates form opposite side walls of a slotted runway and line up with the diameter gauge plates 24 which gradually diverge and form a diameter gauging runway along which the rollers of acceptable length are pushed in spaced relation by fingers 26 on a pair of endless sprocket chains 28, the fingers travelling in the slot of the runway. If the roller is outside the acceptable length tolerances however, it does not reach the diameter gauge plates because a solenoid 30 is energized as will appear in the electrical diagram and retracts the slide 20 which has a headed portion fitting within a notch of the base plate 22 and hence the unacceptable roller drops down between the sprocket chains to chutes 32, 34 and 36. Fig. 8 shows the path of the rollers R, the foremost one in the feed chute engaging the side of the pusher 16, another being advanced by the pusher to length gauging position, another dropping out because unacceptable, and another about to enter the diameter gauging runway.

The slide 20 has a narrow section sliding in a groove in the base plate 22, the top of the guideway being closed by a slotted top plate 38 fastened by screws to the base plate. A pin 40 fixed in a hole of the slide projects upwardly through the slot in the top plate 38 and is connected by a coil spring 42 to an anchor pin 44 fastened in a rearwardly extending lug on a stop plate 46 which is slotted lengthwise and fastened by screws to the base plate. There also projects upwardly from the slide 20 through the slot in the top plate a stop pin 48 which lies below the spring and is arranged to engage the rearwardly projecting lug on the stop plate 46 to limit the forward motion of the slide. The outer end of the slide is pivotally connected by a pin to a forked member 50 having a portion threaded ad-

justably in a link member 52 which is secured pivotally to the plunger of the above mentioned solenoid 30 which is fastened to a bracket 54 under a cover 56.

The pusher 16 is connected yieldably by a pusher rod 60 and a spring 62 to a slide 64 which reciprocates in a guide slot formed by a front guide block 66 and a rear guide block 68, these guide blocks being fastened to the base plate 10 by screws. Spring 62 seats in counterbores in pusher 16 and slide 64. Rod 60 is pinned to slide 16 and projects into a hole beyond the counterbore in slide 64 where it carries a vertical pin 10 which enters a slot in slide 64 to limit the forward movement of the pusher. The guide channel formed between the guide blocks 66 and 68 is covered by a removable top plate 72 which is slotted at the front and fastened by screws to the front guide block. A narrow extension 74 of the top plate overlies the narrow extension of the pusher.

The outer end of the slide 64 has a reduced extension which is pivotally connected by a shoulder screw to a vertical lever 76 which is fulcrumed at 78 on a bracket 80 fastened to the frame. The lever 76 is loosely pivoted to a horizontal slide 82 having a cam follower roller 84 lying in the path of cams 86 on the fingers 26 which push the rollers along the diameter gauging runway below which is a series of chutes 87 for receiving and segregating the gauged rollers. The fingers are carried by the pair of spaced sprocket chains 28 which extend around sprockets 88 on a driven shaft. A coil spring 90 retracts the lever 76 in a direction to cause the connected slide 64 to engage an adjustable stop screw 92 on a bent bracket 94 fastened by a screw to one end of the rear guide block 68.

The upper end of the lever 76 is arranged to engage a roller 100 at a single instant during only a portion of the time one of the work rollers is being gauged. The roller 100 is carried by a lever 102 pivoted to a plate 104 which is yieldably mounted by a leaf spring 106 to a flattened ledge on a bracket 108. The leaf spring is connected to the bracket by a clamping plate 110 and to the plate 104 by a contact clamp 112 which engages the stem of a micro switch 114 mounted for vertical adjustment on the bracket 108. The bracket has its lower slotted portion adjustably secured to screws to the front of the guide block 66. When the lever 76 moves to the right to engage and pass the roller 100, the lever 102 does not pivot because of its shouldered engagement with the plate 104 and hence the leaf spring is flexed upwardly and the stem of the microswitch is instantaneously actuated. As the lever passes the roller 100, the leaf spring returns to horizontal position. When the lever moves to the left again and hits the roller, the lever 102 pivots freely clockwise without causing any actuation of the microswitch. As will later appear, it is important that the microswitch be not closed until the work is between the length gauging members 12 and 18 and that it open before the work passes out between the gauge members. For this reason the gauge members have a width considerably larger than the diameter of the work passing between them and this gives time for the microswitch to close and open during a portion of the gauging interval.

As the roller which is to be gauged for length passes between the fixed gauge block 12 and the movable gauge member 18 the latter takes a position dependent on the roller's length. The

member 18 has its shank adjustably fastened by set screws in a floating block 116 which is supported for lateral movement by two pairs of vertical reed springs 118 which are fastened at their lower ends to the floating block by screws. The upper ends of the reed springs are similarly fastened by screws to a fixed block 120 rigidly mounted on, but overhanging from, a square spacer 122 which is secured on the rear guide block 68. These three parts are fastened rigidly together by two long vertical screw bolts 124, one of which also secures the base of a bracket 126 to the fixed block 120. Short screw bolts 128 also secure the bracket 126 to the fixed block.

To limit the lateral movement of the block 116 in one direction, an upwardly extending lug thereon abuts against a stop screw 130 adjustably secured in a lug depending downwardly from the fixed block 120. A pin 132 is adjustably secured by a set screw in the floating block 116 and abuts against an angular plate or lever 134 which is pivoted by a pair of reed springs 136 to the block 120, the reed springs being secured to the two members by screws and bevelled clamping plates. The angular plate 134 has a horizontal ledge bearing against the stem 138 of an electric gauge 140 which is fastened by screws to the upright portion of the above mentioned standard or bracket 126. It thus appears that any movement of the movable gauge member 18 from normal as the work roller engages it will shift the floating block 116 laterally and control the swinging of the angular plate 134 and so actuate the gauge stem upwardly or downwardly. The gauge 140 is of well known type similar to Dennison 1,894,025 and, as indicated diagrammatically in Fig. 9, has a movable contact member 142 which will make an electric circuit to one side or the other depending on whether the roller being gauged is oversize or undersize.

In operation, the rollers R are suitably urged out of the feed tube, the foremost one engaging the stop plate 14 whereupon the pusher 16 advances it between the fixed gauge block 12 and the movable gauging member 18. If the roller is of acceptable length it is pushed to a supported position on the bevelled edges of the base plate 10 and of the slide 20. Then it will be advanced rearwardly along the diameter gauging runway by the fingers 26 on the sprocket chains. If the roller being gauged for length is outside the tolerances, the slide 20 is withdrawn by the solenoid 30 and the roller drops down and is eliminated. The electrical hook-up is indicated in Fig. 9 and includes a relay coil 146 which will actuate a make-before-break switch having blades A and B. Blade A will close a circuit before B opens another and B will close before A opens. A relay coil 148 controls blades D and C.

Whenever the lever 76 is actuated by a cam 86, a roller is pushed between the gauging members 12 and 18 and the micro switch 114 is closed for an instant and immediately opens. Hence the relay coil 146 will operate at every cycle and close the right hand switch blade A before the left hand blade B opens but no circuit whatever will be completed as long as the work roller is within the acceptable limits because no current can go through the gauge as long as the movable gauge arm 142 is in a neutral position. When the roller leaves the gauging members, the gauge arm 142 will engage the undersize contact due to spring pressure in the gauge but such contact is idle because the microswitch 114 has already opened, thus de-energizing the relay 146 and

restoring its switch blades A and B to the starting position. In other words, the work gets between the gauge members 12 and 18 before the microswitch is closed and remains there until after the microswitch opens. Otherwise there would be an energizing of the solenoid 30 for each work piece regardless of length.

Assume now a work roller of unacceptable length reaches gauging position and that the microswitch 114 closes as usual for an instant. One or the other of the gauge contacts is engaged by the movable arm 142 of the gauge and a circuit is completed through the upper relay coil 148, thus closing the switch blades C and D. The solenoid 30 is thereupon energized through a circuit including a wire E and the right hand blade C to retract the slide 20 preparatory to dropping the roller. Once energized, the solenoid remains so for a time because the opening of the microswitch occurs before the work leaves gauging position, thus de-energizing the relay 146 and closing the left hand switch blade B before the right hand blade A opens and so completing a holding circuit for the upper relay 148 through the wire F and the left hand switch blade D. The holding circuit persists and keeps the solenoid 30 energized until the microswitch is again closed by the next advance of the lever 76 and the work pusher 16. This opens the holding circuit by energizing relay 146 and so opening the switch blade B. If the next piece is acceptable, the circuit through the gauge 140 is also broken so that the relay 148 will not be energized because the gauge arm 142 takes a neutral position and keeps it until after switch blade A opens. Thus the solenoid is de-energized and remains so until another unacceptable roller is gauged.

I claim:

1. In a gauging machine, a runway, a pair of relatively movable gauging members, a pusher for pushing articles between the gauging members to the runway, a movable contact member actuated by one of the gauging members to complete a circuit if the article is of unacceptable size, means controlled by the completed circuit to interrupt the continuity of the runway and thereby discharge such article, an endless conveyor for advancing acceptable articles along the runway, and cams mounted on the conveyor for repeatedly actuating the pusher.

2. In a gauging machine, a runway having a section movable to interrupt its continuity, a pair of relatively movable gauging members, a pusher for advancing articles between the gauging members to the runway, a movable contact member, means for transmitting motion of one of the gauging members to the movable contact member to prepare a circuit if the article is either over-

size or undersize, a solenoid energized when the circuit is completed for retracting the movable section of the runway, and means actuated by the next advance of the pusher with an acceptable article for deenergizing the solenoid.

3. In a gauging machine, a runway having diverging sides, a movable section in the runway, a pair of gauging members adjacent to the movable section, means for passing articles between the gauging members to gauge one dimension of the article, means controlled by the gauging operation to retract the movable section and discharge an article when the article is unacceptable in said one dimension, and means for advancing articles acceptable in said one dimension along the runway to thereby gauge a second dimension.

4. In a gauging machine, a slotted runway, a fixed gauging member, a movable gauging member, the gauging members being spaced apart in the direction of the length of the runway and at one side of the runway, a pusher at one side of the runway for advancing articles through the gauging space between the gauging members onto the runway, a movable contact member actuated by the movable gauging member to complete a circuit if an article is either oversize or undersize, a single electrically actuated slide normally forming a section of the runway and retractable when the circuit is completed to interrupt the continuity of the runway and discharge oversize or undersize articles from the runway, and a conveyor having fingers entering the runway slot for conveying articles of acceptable size along the runway out of the way of following articles.
